UNITED STATES PATENT OFFICE.

LOUIS K. SCHWALL, OF CHICAGO, ILLINOIS.

BROILER.

1,178,823.

Specification of Letters Patent. Patented Apr. 11, 1916.

Application filed May 1, 1915. Serial No. 25,106.

To all whom it may concern:

Be it known that I, LOUIS K. SCHWALL, a citizen of the United States, residing at Chicago, in the county of Cook and State of Illinois, have invented a certain new and useful Improvement in Broilers, of which the following is a full, clear, concise, and exact description, reference being had to the accompanying drawings, forming a part 10 of this specification.

This invention relates to improvements in broilers.

An object of the invention is to provide a broiler more particularly adapted for use 15 in restaurants and the like, which has means for relatively adjusting the grid iron and the heat producing means, to thereby insure the best results in cooking of the food.

Another object of the invention is to provide a broiler so arranged that the food on the grid iron may be cooked from the top, by means of a gas burner, or from beneath by means of charcoal, or other suitable fuel, on a fire bed.

25 The invention furthermore consists in the improvements in the parts and devices, and the novel combinations of the parts and devices as herein shown, described, or claimed.

In the drawing forming a part of this 30 specification, Figure 1 is a front elevation of a broiler showing my improvements in connection therewith; Fig. 2 is a side elevation upon a reduced scale of the broiler illustrated in Fig. 1; Fig. 3 is a vertical 35 transverse section taken substantially on the line 3—3 of Fig. 4; Fig. 4 is a vertical sectional view at right angles to that shown in Fig. 3, and taken on the line 4—4 of Fig. 3; Fig. 5 is a detailed horizontal sectional 40 view taken on the line 5—5 of Fig. 3; Fig. 6 is a broken, detail sectional view similar to Fig. 3 but upon an enlarged scale; and Fig. 7 is a detailed perspective view of a cam employed with my improvements.

45 In said drawing, "A" designates the outside frame of the improved broiler, and the front wall thereof preferably comprises two portions, 11 and 12, offset from each other, the upper portion 12 having its lower 50 edge terminating in an outwardly and downwardly inclined flange 14. The front wall is cut away between the flange 14, and the upper edge of the portion 11, to thereby provide an opening 13, through which access may be had to the grid iron and interior 55 of the broiler proper.

As shown, the broiler is provided with a plurality of gas burner pipes 15, above which is disposed a horizontal asbestos, or other heat resisting, partition 16. The partition 16 forms the bottom wall of a warming chamber 17, having a pivoted front door 18, mounted on hinge pins 19, and adapted to be manipulated by a handle 20. An escape for the gases of combustion from the 60 broiler is provided by means of the outlet pipe 10. (See Fig. 4.)

A dripping pan 20 is provided below the gas burners and substantially on a horizontal plane with the upper edge of the portion 70 11 of the front wall of the broiler, said dripping pan 20 having a centrally located outlet 21 through which the drippings are adapted to fall into a drawer 22, slidably mounted in the lower portion of the broiler 75 and adapted to be withdrawn from the front thereof, as by means of a handle 23. Extending around the inner side walls of the broiler at the top of the dripping pan 20 is a ledge 24 on which is adapted to be removably seated a sheet 25 on which may be placed a layer of sand and fire brick 26, to thereby form a bed for a charcoal, or coal, or other suitable fuel, fire.

80 Adjustably mounted between the fire bed 26 and the gas burners 15 is a horizontally disposed grid iron 27, having antifriction rollers 28 secured thereto on its side edges, the rollers 28 riding back and forth upon tracks 29, formed by angle irons 30, which are vertically adjustably mounted, as hereinafter described. Secured to the sides of the grid iron 27 are U-shaped clips 31, which extend around and under the tracks 29, and thus serve to guide the grid iron and keep it in proper position, as it is pulled out and pushed back. The angle irons 30 are secured to the upper ends of a pair of outwardly turned channel shaped members 33, one at each side of the broiler. The channels 33 are slidably mounted upon, and guided by inwardly turned channels 34, secured to the side walls of the broiler by means of spacers 35 and bolts 36 (see Fig. 6). The 90 channel shaped members 33 are connected by transversely extending cylindrical pipe 37, with which engages a cam 38, the latter being substantially channel shaped in cross section, and fitting over the pipe 37, as appears from Figs. 3, 4 and 7. The cam 38 is secured to an oscillatable shaft 39, mounted 100 in suitable bearings in the front and back 105 of the broiler.

2
wall of the broiler, the shaft 39 being extended at its front end outside of the front wall 11, and having secured thereto a short lever arm 40. Slidably mounted on the lever 40 is a hand lever 41, which carries on its inner face a pawl 42, adapted to coöperate with a stationary rack 43, rigidly secured to the front wall of the broiler. Within the broiler, and near its innermost end, the shaft 39 has a lever 44 rigidly secured thereto and slidably adjustably mounted on the lever 44 is a counterbalance or weight, 45.

As most clearly shown in Figs. 1, 2 and 3, the gas burners 15, are supplied from a main pipe 47, from which lead branch pipes 48—48, the supply of gas to each of the branch pipes 48 being controlled by suitable means, such as a globe valve 49. In each of the branch pipes 48 is placed an air injector, 20 or mixing device 50.

On each side of the broiler is secured a sheet 51, the lower edge of which is inwardly bent, as indicated at 52 to thereby cause any drippings to drain over into the 25 dripping pan 20.

From the preceding description it will be seen that the means for adjusting the grid iron 27 are simple and efficient; they permit of any degree of adjustment desired between the grid iron and the heat producing means; the hand lever 41 is placed in a convenient position to thereby encourage the cook, or operator, in always properly adjusting the heat for the material being 30 cooked; the broiler may be adapted for cooking the food, either from the top or from the bottom, as desired; and by mixing the gas and air and controlling the supply of gas and air to the gas burners on the 35

outside of the broiler, better combustion is obtained, and proper adjustment of the gas flame is encouraged, since the adjusting valves 49 are readily accessible to the cook and are always in a cool condition, thus overcoming the objection heretofore encountered, 45 wherein the supply of gas for the burners has been controlled by valves or cocks located within the broiler.

Although I have herein shown and described what I now consider the preferred embodiment of my invention, yet I am aware that changes and modifications may be made in the details of construction and arrangement of parts, without departing from the spirit of the invention, and I contemplate all such changes and modifications as come within the claim appended hereto.

I claim:

In a broiler, the combination with a suitable frame having heat producing means located therewithin, of a grid iron vertically adjustably mounted within said frame, means for adjusting said grid iron, said means including depending vertical arms, a horizontally extending brace rod connecting said arms, an operating shaft extending at right angles to said rod and located below the same, and a cam carried by said shaft, said cam having a grooved periphery within which slides said rod.

In witness that I claim the foregoing I have hereunto subscribed my name this 8th day of April, 1915:

LOUIS K. SCHWALL.
